UNITED STATES PATENT OFFICE

WALTER L. DIXON, OF BOSTON, MASSACHUSETTS, ASSIGNOR TO REECE FOLDING MACHINE COMPANY, OF BOSTON, MASSACHUSETTS, A CORPORATION OF MAINE

INFOLDING MACHINE

Application filed May 27, 1930. Serial No. 456,054.

This invention is a novel infolding machine, namely of the class used for folding in the margins of cloth blanks for collars, cuffs or other apparel. The invention may be applied to a power driven automatic infolding machine constructed for the production of folded "collar band" blanks of a shape wherein one or both ends of the blank are rounded, without angular corners.

A special object of the present invention is to afford a system of infolders and operating mechanism adapted for the effective folding of each of the rounded ends of narrow blanks, such as the collar bands referred to, it having been a difficult undertaking to fold these rounded ends in a manner to give a smooth outline in the product and to avoid the irregularity or bunching of the inturned fabric which is liable to occur, and which impairs the appearance and value of the product.

The present invention, for the attainment of the aforesaid objects and advantages, consists in the novel construction and operation of infolding machine, and the novel features of combination, arrangement and detail herein illustrated or described.

The present application is a companion to another application executed and filed the same date herewith Serial Number 456,053 and which shows the complete infolding machine, as to defining and pressing as well as infolding means. For this reason the drawing herein discloses only the infolding mechanism of this invention, and this may be considered as substituted for the infolding mechanism shown in the companion application, as the two may be interchangeable in the same machine, and each having features of advantage according to the particular product to be made.

The companion case contains figures showing general front and right side elevations of the complete machine, and a transverse vertical sectional view, and certain detail views which may be referred to for the purposes of the present disclosure.

In the accompanying drawing, Figure 1 is a partial top plan view of the machine, shown with a certain plate removed, and

showing the infolders in their outer or retracted position ready to receive the unfolded blank.

Fig. 2 is a longitudinal vertical section view taken on the line 2—2 of Fig. 1, certain parts seen in front elevation.

Fig. 3 is a top plan view similar to Fig. 1, but in a later stage, wherein the infolders have moved in over the templet to form the folds.

Fig. 4 is a transverse vertical section on the line 4—4 of Fig. 3.

Fig. 5 is a face view of the product or folded blank, with the original outline of unfolded blank indicated in dotted lines.

These figures correspond substantially with Figs. 5, 7, 6, 9 and 8 respectively of the companion case.

The blank *a* is shown in dotted lines in its original size and shape and in full lines in its final folded condition wherein the side margins *b* at the front and rear have been turned in and the end margin *c* has been neatly turned in and pressed down on the principles of this invention.

The machine is preferably power driven from a cam shaft as in the companion case. The frame of the machine carries a fixed bed 21, the center of which is slightly raised as a pedestal or so-called pad 22 on which the blanks rest during infolding. The bed may have longitudinal slots 23 for the adjustment of the parts of the pad and for other purposes. The templet 27 is indicated in Fig. 3 as having a middle plate 35 and end plates 36. The templet is fitted to descend upon the blanks on the pad while the infolders normally lie flush with the top of the pad. The complete construction of the templet is not herein shown, but a carrier 37 is indicated for the middle plate and a carrier 43 for the end plate, this arrangement permitting the templet to be contracted or shortened when elevated, to permit the extraction of the folded blanks.

The system of infolders may be carried on an outline carriage or frame, similar to that in the companion case, comprising a front frame bar 63 and a rear frame bar 63^a, the two interconnected at the ends to permit its relative approach and separation, by a telescoping ac-

tion. Each frame bar is formed with slots 68 for the adjustable attachment of infolders.

The infolders are shown as including a middle side infolder 72 at the front and a similar one 72^a at the rear, these attached to the respective frame bars by bolts 73. Each infolder may comprise a thick or heavy body portion with a thin plate-like overhanging portion 74, these portions adapted to ride over the pad and templet while the thick portions move up to the sides of the pad during the infolding action as will be clear from Fig. 4.

Next to the middle side infolders are what may be termed end side infolders 76 and 76^a at the front and rear, so that each of the long sides of the blank is folded by means of the three side folders described. Figs. 1 and 2 show the cover plate removed from the rear end side folder 76^a, thus showing the construction. Each end side folder is shown as having an endwise extension 77 or 77^a, the top side of which is flush with the body of the infolder, but partially recessed at 78 or 78^a to receive a thin infolder to be described. The top sides of the folders 76 and 76^a also are formed with shallow recesses 80 for the reception of a yielding folder to be described. The respective end side folders are attached to the frame side bars by means of bolts 81 and 81^a, permitting lengthwise adjustment for changes of size.

On top of each end side folder is attached a cover plate 82 or 82^a, the latter being omitted except in Fig. 4. These cover plates are substantially a part of the infolder, being attached by screws thereto. Each cover plate is substantially co-extensive with its folder excepting along the folding outline, where the cover plate is set back further than the edge of the infolder, so that the cover plate constitutes a positioning means or gage aiding in correctly inserting the unfolded blank. Each cover plate has a slot 83 for a pin 98 to be described.

The reference numbers thus far used correspond substantially with the same reference numbers in the companion case.

Instead of a single end folder at the end or apex of the blank, the present construction embodies a pair of end infolders 89 and 89^a connected to each other by a pivot pin 90 so that they may move bodily lengthwise and also swing toward each other about the pivot pin with a scissor-like motion. These swinging end folder plates are thin plates moving in the recess 78 of the end side folder. Before describing the means for giving the endwise movement to the end folders the connections for swinging will be described.

The end folders 89 and 89^a are provided with upstanding pins 91 and 91^a engaging in slots 92 and 92^a formed in plates 93 and 93^a attached to the end side infolder. These slots are longitudinal and are adapted, when the end side infolders move toward each other, to

swing inwardly the pins 91 and 91^a and thus swing the end infolders toward each other.

The endwise movements of the end infolders may be effected as follows. A slide 94 is shown movable longitudinally in a guiding groove 23 in the machine bed. The inner end of this slide carries the pivot pin 90 already referred to, so that the movements of the slide cause the longitudinal movements of the end infolders. The outer end of the slide 94 has an upstanding projection 95 to which is pivoted a push rod 103 having an adjusting slot 104, this rod and slot corresponding with the same parts in the companion case and being arranged for similar actuation, preferably the endwise inward movement of the end folders preceding their swinging movement produced by the mutual approach of the side infolders.

In order to maintain a continuous outline during the initial movements of the infolders it is preferred to employ a yielding folder 97 or 97^a which is arranged to slide in the recess 80 or 80^a of the end side folders and to bridge over the gaps between the end side folders and the end folders, as clearly shown in Figs. 1 and 3. Each yielding folder may have an upstanding pin 98 or 98^a extending through the slot 83 or 83^a of the cover plate and pulled upon by a spring 99 or 99^a to maintain the folder yieldingly in contact with the adjacent folders.

The full complement of infolders surrounding the templet and blank have now been described, involving a total of fourteen infolders, in the full embodiment. They are shown in Figs. 1 and 2 in their outward initial position and in Figs. 3 and 4 in their inward position after the folding and in readiness for the pressing operation. The blank *a* is omitted in Fig. 1, but its outline will correspond substantially with the dotted outline indicating the boundary of the thin infolder edge 74. Fig. 3 shows the folded blank *a* and two of its folds *b*.

The end infolders 89 and 89^a must necessarily overlap at their pivot pin and in order to preserve a continuous outline each of them is indicated as recessed for a part of its depth to accommodate the other. For example each of them may be recessed for half of its depth over the area of a concentric circle tangent to the outline to be infolded, as shown.

At the completion of the folding it is intended to effect a squeezing pressure between the infolders and underlying pad to crease the folds, and the pad may be heated to improve the action.

The actuating means and the cams for effecting the various infolder movements may be as in the companion case, and the timing may be substantially the same. Therefore the details of the connections and cams are omitted herefrom. It will be understood that the infolders before moving inwardly

must be lifted from their initial position shown in Fig. 2, with their top sides flush with the pad, to an elevated position as shown in Fig. 4, permitting the folders to be moved in over the pad and templet. The 5 means for effecting the lifting and lowering movements and the pressing movements of the infolders may be as in the companion case.

Having described an illustrative embodiment of the improvements, it should be mentioned that mere matters of design and detail are not intended as limitations except to the extent specified in the claims:

What is claimed is:—

- 15 1. In a machine for infolding the opposite side edges and both rounded ends of collar band or similar blanks, in combination with a blank supporting bed and a defining templet, of infolders for the opposite side edges of the blank movable inwardly and outwardly, and at the end a complementary pair of infolders swingably connected together, means for moving the pair of end infolders inwardly endwise, means for moving the opposite side edge infolders inwardly sidewise, and means carried by the opposite side edge infolders respectively for swinging the adjacent end infolders toward each other.
- 20 2. A machine as in claim 1 and wherein the end infolders overlie the adjacent side edge infolders respectively, and the side edge infolders are recessed to accommodate the end infolders.
- 25 3. A machine as in claim 1 and wherein the means for swinging the end infolders comprises a constantly engaged slot and pin connection between the side edge and end infolders.
- 30 40 4. In testimony whereof, this specification has been duly signed by:
WALTER L. DIXON.
